SHOWER STALL

George Dewey Swan, Stanwick Road, Cos Cob, Conn.

Filed Mar. 29, 1962, Ser. No. 69,494

Term of patent 14 years

(Cl. D4—3)

FIG. 1

FIG. 2

FIG. 1 is a perspective view of a shower stall embodying my new design; and

FIG. 2 is a sectional plan view thereof taken on the line 2—2 in the direction of the arrows as indicated in FIG. 1.

The side opposite that shown in FIG. 1 is substantially plain as best seen in FIG. 2.

The dominant features of my design reside in the portions shown in full lines.

I claim:

The ornamental design for a shower stall, as shown and described.
